UNITED STATES PATENT OFFICE.

FRANK P. POLASKI, OF GRANITE, OKLAHOMA TERRITORY.

POWER-HAMMER.

No. 808,256.

Specification of Letters Patent.

Patented Dec. 26, 1905.

Application filed March 13, 1905. Serial No. 249,799.

To all whom it may concern:

Be it known that I, FRANK P. POLASKI, a citizen of the United States, residing at Granite, in the county of Greer, Oklahoma Territory, have 5 invented a new and useful Power-Hammer; and I do hereby declare the following to be a full, clear, and exact description of the invention, such as will enable others skilled in the art to which it appertains to make and use the 10 same.

My invention relates to improvements in power-hammers, and has for its object to provide an apparatus of this general character which will combine in its construction and operation a strong, durable, and light framework with great force, power, and ease of operation of the several working parts.

My invention consists, essentially, of a power-hammer comprising an open - slotted 20 frame connecting with an anvil-post carrying the anvil at one end and with vertical side beams at the opposite end, a rock-shaft fulcrumed on said beams and provided at its front end with means for adjusting a hammer there- 25 in and at its rear end with a ball-and-socket joint connecting with a swiveled frame carrying an elliptical spring, a foot-lever, and means for connecting the same with the rock-shaft.

My invention further consists in the novel 30 construction and general arrangement of parts hereinafter fully described, illustrated in the drawings, and particularly pointed out in the claim.

In the drawings forming part of this specification, wherein like numerals of reference 35 designate corresponding parts, Figure 1 is a side elevation of a power-hammer embodying the essential features of my invention, and Fig. 2 a detail view of the ball-and-socket 40 joint connecting with the rear end of the rock-shaft.

Referring to the drawings, the numeral 1 designates the base of the framework, which is capable of being readily secured to a floor 45 or other proper foundation and having the anvil-post 2, preferably formed integral therewith to provide a strong, rigid, and reliable base.

The vertical side beams 3 project upwardly 50 from the rear part of said base 1, to which they are suitably attached, one on each side thereof or formed integral therewith, if deemed preferable, said beams and the side bars 4 constituting an open frame to secure 55 lightness and strength, and the front ends of

said bars being suitably bolted to the anvil-post 2, carrying the anvil 2', while near their rear ends said bars are also suitably bolted to the vertical side beams 3. The extreme rear ends of the side bars 4 incline inwardly toward 60 and touch each other and are held securely in place by a suitable cross-bolt 5, as fully shown in Fig. 1.

The rock-shaft 6 has its bearings or fulcrum in the tops of the side beams 3, and the front 65 end of said rock-shaft is provided with an elongated open slot 7 for the reception and adjustment therein of the handle 8 of the hammer 9. The handle of said hammer is adjusted at the desired position in said slot 7 and securely held 70 in such position by means of the clips 10 and screw-bolts and nuts 11, while to the extreme rear end of said rock-shaft is pivoted the upper end of the ball-and-socket joint 12, the ball wherein is formed integral with a screw- 75 threaded bolt 13 which projects downwardly and engages with a corresponding opening in the top bar of the open frame 15, said screw-threaded bolt 13, being provided with a squared shank 14, whereby said bolt may be turned and 80 adjusted in the desired position in the head of the open frame 15 to regulate and control the area of motion of the hammer 9.

The open frame 15 is composed of the head 85 or top bar connected with the two downwardly-projecting side rods, the lower ends of which are screw-threaded and adapted to engage with corresponding openings in the projecting ears or lugs of the rectangular clip 16, which incloses the central portion of the lower member 90 of the elliptical spring 17 and holds it securely in place therein, the upper member of said spring resting against the lower rear ends of the side bars 4, to which it may be securely connected if deemed desirable. 95

The foot-lever 18 is preferably bifurcated at its rear end and suitably journaled between the vertical side beams 3, while its front end is provided with a loop 19, encircling the anvil-post 2, thus forming a foot-treadle which 100 may be easily operated on all sides of said anvil-post, as fully shown in Fig. 1 of the drawings. A bifurcated rod 20 is pivoted to the foot-lever 18 at its lower end and to the rock-shaft 6 at its upper end in such manner that 105 by the depression of said foot-lever 18, by means of the foot-treadle 19, the rock-shaft is actuated, compressing the elliptical spring 17 and bringing the hammer 9 down upon the anvil or upon the article to be operated upon, 110

the elliptical spring 17 serving to immediately restore the hammer and its operative parts to normal position.

Having thus described my invention, what I claim as new, and desire to secure by Letters Patent, is—

A power-hammer, comprising a framework having an anvil thereon, a hammer to coöperate therewith and carried by a fulcrumed beam, 10 a flexible joint carried by one end of said beam, a screw-threaded shank projecting from said joint, a U-shaped member adjustably connected to said shank, and an elliptical spring resting

under or secured to a stationary part of the framework and passing between the sides of 15 said U-shaped member, the lower portion of said spring being connected to the sides of said U-shaped member and adapted to restore the hammer to its normal position.

In testimony whereof I have hereto affixed 20 my signature in the presence of two witnesses.

FRANK P. POLASKI.
